AUTOMATIC PRESSURE PUMP

Adolph Bornholt, Yellow Grass, Saskatchewan,
Canada

Application December 8, 1931. Serial No. 579,806

1 Claim. (Cl. 103—211)

This invention relates to improvements in a pressure pump, the primary object being to provide a type of pump which eliminates the heavy manual practice of pumping, this being accomplished by employing a heavy weight of circular proportion which snugly engages the sides of a well exerting a downward pressure on the water which results in the water rising upwardly through a centrally located pipe.

10 A further object is to provide a type of pump which employs a windlass having an elongated lever bar with ratchet attachment for raising the pressure weight.

With these and other objects in view, as will 15 appear as the description proceeds the invention consists in the design, construction and arrangement of parts as hereinafter more specifically set forth, claimed and shown in the accompanying drawing forming a part of this present application and in which.

20 Fig. 1 is a vertical sectional view showing the arrangement of the pump as installed in a standard open type well.

Referring more in detail to the drawing in 25 which similar characters represent corresponding parts throughout the drawing, it will be seen that the invention consists of a casing 11 positioned in the lower normal water limits of a well 10, said casing conforming to the well diameter 30 and being provided at its upper end with a tapered edge 12. The tapered edge 12 should rise to the normal high water level of the well.

A heavy weight 13 constructed of cement or 35 any suitable composition is slidably arranged in the casing 12, said weight 13 making snug engagement with the side of the casing 12, the tapered edge 12 permitting the weight to readily enter the casing.

Upwardly extending through the weight, is a 40 pipe 14, said pipe 14 making sliding engagement within a rigidly positioned pipe 15. The pipe 14 may project slightly below the weight 13 and is secured to the weight by the threadably engaging nuts 16 and 17. Th portion of the pipe 14 slidably arranged in the pipe 15 is of sufficient lengths to permit the weight to be lowered to near the bottom of the well 13 and is arranged to permit upward travel of the weight to the normal high water level. Th pipe 15 is rigidly secured by the 50 upper and lower braces 19 and 20 respectively and is provided with a packing boss 21 at the lower end, thus preventing the water from leaking at this point.

Upwardly extending from the pipe 15 is the 55 pipe 22, said pipe 22, being threadably secured to

the pipe 15, thus permitting convenient assembly of the co-operating parts, the pipe 22 extends upwardly past the well platform 23 and turns to terminate in the outlet nozzle 24. The pipe 22 is further provided with the lead pipe 25 for house 60 or any underground lead and a suitable shut-off valve 26 is positioned above the well platform.

For purposes of raising and lowering the weight 13, a windlass 27 is mounted above the well platform and suitable steel cables 31 extend from each end of the windlass downwardly to eye bolts 28 which are firmly secured diametrically of the weight 13. The windlass is provided with the lever arm 29 and the ratchet gear 30, thus the heavy weight can be raised with a minimum 65 70 amount of effort as compared with the ordinary type handle, while the ratchet control enables the operator to raise or lower the weight without danger of the device becoming uncontrollable.

It is believed that the design, construction and 75 arrangement of the invention are apparent from the foregoing paragraphs taken in conjunction with the accompanying drawing without further detailed description.

While the preferred embodiment of the invention 80 has been disclosed, it is understood that minor changes in the details of construction, combination and arrangement of co-operating elements may be resorted to within the scope of what is claimed without departing from the 85 spirit of the invention.

What I claim is:

A pressure pump for wells comprising a tubular casing mounted in the lower normal water limits of the well, a circular weight slidably mounted in 90 said casing, a pipe extending through the center of said weight for conducting water from beneath the weight, nuts adjustably securing said weight on said pipe, a tubular sleeve rigidly supported in the well above said weight and axially 95 thereof, adapted to telescopically receive the upper end of said pipe, a second pipe fixedly secured to the upper end of said sleeve and extending above the top of the well to provide an outlet, packing at each end of said sleeve establishing a 100 water-tight connection between said sleeve and pipes and means for raising and lowering said weight.

ADOLPH BORNHOLT.
